UNITED STATES PATENT OFFICE.

EDWARD ALBERT MITCHELL, OF LONDON, ENGLAND.

INTERNAL-COMBUSTION ENGINE.

SPECIFICATION forming part of Letters Patent No. 658,993, dated October 2, 1900.

Application filed March 8, 1899. Serial No. 708,209. (No model.)

To all whom it may concern:

Be it known that I, EDWARD ALBERT MITCHELL, a subject of the Queen of Great Britain, residing at 66 Thornlaw road, West Norwood, 5 London, in the county of Surrey, England, have invented a new and useful Improvement in Internal-Combustion Engines, of which the following is a specification.

My invention relates to an improved internal-combustion engine.

The object of my said invention is to provide an engine in which a working stroke may be given to the piston once during every revolution of the crank-shaft without the use of 15 a force-pump for compressing the motive fluid, as commonly employed in engines of the type under consideration. In place of this pump I provide a closed chamber in which the motive fluid is under pressure, and the pressure 20 which I contemplate making use of is that occasioned by the production of combustible gas in a confined space—as, for instance, by the action of dilute acid on granulated zinc or by the action of water upon a combination 25 of calcium and hydrocarbon or upon calcium carbide or any other similar compound. The gas under pressure is thus generated immediately in connection with the engine in which it is to be employed and is supplied direct 30 thereto.

In the accompanying drawings, Figure 1 is an elevation of an improved engine constructed according to my invention. Fig. 2 is a vertical section of the cylinder and adjacent 35 parts of the same. Fig. 3 is a plan view, portions of the same being removed; and Fig. 4 is a section on the line 4-4, Fig. 1.

1 is the generator or reservoir holding the compressed motive fluid, and 2 the pipe connecting said generator with the feed-valve 3 40 of the engine. Said pipe is provided with a stop-valve 4 and a reducing-valve 5 of any suitable type.

6 is the cylinder of the engine, which is provided with a water-jacket 7, as usual in engines of this type.

8 is the piston; 9, the piston-rod; 10, the cross-head; 11, the connecting-rod; 12, the crank, and 13 the crank-shaft, which is supported in suitable bearings 14, mounted on the bed-plate 15 of the engine.

The cylinder 6 is supported on a casting 16, which also forms the guides for the cross-head 10.

17 is the exhaust opening from the cylinder, 55 and 18 another opening by which air can enter the cylinder through a chamber 19 when the valve 20 is open. Said valve, which is normally maintained closed by a spring 21, is controlled by a cam 22, supported on the 60 shaft 23. At the lower end of the cylinder is a second opening 24, which communicates, through the pipe 25, with the chamber 19, the open end of said pipe projecting into the opening 18 above mentioned.

65 26 is a valve located at the entrance to pipe 25 and normally maintained closed by a spring 27. Said valve is controlled by the cam 28, also secured to shaft 23. Said shaft 23 is supported in bearing 29 and is driven through 70 gear-wheels 30 31 from the crank-shaft 13. The shaft 23 is provided with a governor 32 of any suitable type, the movable portion 33 of which carries an arm 34, adapted to engage with an inclined block 35, secured to a 75 lever 36. This lever is provided with a fixed pivot 37 and is connected by a link 38 with the feed-valve 3. Said feed-valve is normally maintained closed by a spring 39 in the usual manner.

80 The igniting device may be of any suitable construction, that shown in the drawings being, for example, an electrical device consisting of a platinum wire 40, joined in series with a battery 41 or other suitable source 85 of electrical energy. Said igniting device is located at the place where the motive fluid enters the cylinder.

42 is a stop-cock provided in the opening 24 for a purpose hereinafter mentioned.

90 The operation of my improved engine is as follows: The gas, which is either generated or stored under pressure in the chamber 1, passes through pipe 2 and reducing-valve 5, through stop-valve 4, when the latter is open, and feed-valve 3 into the cylinder 6 above the piston. With the parts in the position shown in Fig. 2 the piston is at the upper end of its stroke and is about to move down, the valve 20 is closed, and the air in the upper part of the 100 cylinder has been compressed through the previous upward stroke of the piston. The amount of air in the cylinder is sufficient to more than support combustion of the motive fluid supplied during the working stroke. 105 The valve 3 being open by the action of arm 34 on block 35, thereby raising the lever 36, the gas which is stored or generated in the

chamber 1 and the pressure of which is greater than that of the air compressed in the cylinder 6 during the previous back stroke of the piston flows into the cylinder, 5 impinging against the igniting device at 40, being thereby ignited and heating the compressed air or moisture in the cylinder. The piston thereupon moves downward, the valve 3 being maintained open for a suitable length 10 of time, which is determined by the operation of the governor 32. After the valve 3 has closed, the heated air in the cylinder continues to expand, moving the piston P forward until the exhaust-port 17 is uncovered by the 15 piston and the upper part of the cylinder is opened to the exhaust. During the downward motion of the piston the air in that part of the cylinder below is forced out first of all through the exhaust-port 17; but when said 20 port is covered by the piston, the valve 26 being open, the air escapes through the pipe 25 into the chamber 19. Almost immediately after the upper part of the cylinder is opened to exhaust through port 17 the valve 20 is 25 caused to open by the operation of the cam 22, and air rushes in through the opening 18, chamber 19, and through the cylinder and exhaust-port 17, thereby clearing out the 30 products of combustion. The direction of the current of air through the cylinder is determined by the fact that the exhaust-port 17 is opened before the valve 20 opens. Just before the piston reaches the bottom of its 35 stroke the valve 26 is, owing to the shape of the cam 28, permitted to close under pressure of the spring 27, and the air remaining in the lower portion of the cylinder is slightly compressed. Before, however, the piston has reached the dead-point said valve is opened 40 again and the compressed air permitted to rush out through the pipe 25. As the piston moves forward on its upstroke, the valve 20 will remain open until just before the piston covers the port 17, the remainder of the up- 45 stroke serving to compress the air in the upper portion of the cylinder until when the piston reaches its uppermost position the feed-valve is again opened and the cycle recommences.

50 If the cock 4 is closed, the supply of motive fluid to the engine is cut off, while if the cock 42 is closed the air remaining in the lower part of the cylinder when the piston has covered the port 17 will be compressed during 55 the forward motion of the piston, or a vacuum will be formed if the piston is moving backward. In either case the movement of the piston will be arrested.

It will be understood that my invention is 60 not restricted to the precise type of engine illustrated, but that other types of engine may be readily constructed in accordance with my invention.

What I claim is—

65 1. In a continuous-combustion gas-engine having an impulse every revolution, the com-

bination of a generator for generating combustible gas under pressure, a valve for admitting air to the cylinder during the latter part of the outstroke and during the first portion of the return stroke, means for closing said valve during the latter part of the return stroke, a valve for admitting the gas under pressure direct from the generator to the cylinder during the first portion of the working 75 stroke of the piston said valve being closed during the latter portion of the working stroke, and means for igniting the gas while the same is being admitted to the cylinder. 70

2. In an internal-combustion engine having an impulse every revolution, the combination of a generator for generating combustible gas under pressure, a cylinder closed at both ends, a piston movable in said cylinder, a valve for permitting the escape of air in 80 front of the piston during the working stroke, a valve for admitting air to the cylinder during the first portion of the return stroke of the piston, means for closing said valve during the latter portion of said return stroke, a 85 valve for admitting the motive fluid under pressure from the generator to the cylinder during the first part of the working stroke of the piston, said valve being closed during the latter part of the working stroke, and means 90 for igniting the motive fluid while the same is being admitted to the cylinder, substantially as described. 95

3. In an internal-combustion engine having an impulse every revolution, the combination of a cylinder closed at both ends, a piston movable in said cylinder, a chamber open to the air and connected through another opening to the rear end of the cylinder, a valve for closing said opening during the latter part of the return stroke, and the first 100 part of the working stroke of said piston, a pipe connecting the space in front of the piston with the atmosphere, and projecting into the chamber, connected with the rear part of 105 the cylinder, a valve in said pipe, and means for closing said valve for a short time before the piston reaches the end of its working stroke, substantially as described. 110

4. In an internal-combustion engine having an impulse every revolution, a cylinder, a piston, movable in said cylinder, an exhaust-port opening out of said cylinder, means for opening said port before the piston reaches the end of its working stroke, a chamber open 115 to the air and connected through another opening to the rear end of the cylinder, a valve in said opening and means for opening said valve after the opening of the exhaust-port, and closing same before the closing of 120 said port. 125

In witness whereof I have hereunto set my hand in presence of two witnesses.

EDWARD ALBERT MITCHELL.
